United States Patent Office

Des. 183,732

Patented Oct. 21, 1958

183,732

WATCH

Stephen Fedor, Lancaster Township,
Lancaster County, Pa.

Application December 21, 1955, Serial No. 39,411

Term of patent 14 years

(Cl. D42—8)

FIG. 1

FIG. 2

Figure 1 is a top plan view of a watch showing my new design; and

Figure 2 is a reduced side elevational view thereof.

Certain parts of the watch are colored as shown in Figure 1.

I claim:

The ornamental design for a watch, as shown and described.
